UNITED STATES PATENT OFFICE

WILLIAM A. KNAUER, OF PHILADELPHIA, PENNSYLVANIA

AIR INFLATED BLADDER

Application filed April 19, 1930. Serial No. 445,735.

This invention relates to rubber bladders or the like and more particularly to an air inflated bladder adapted for use in a ball such as a football, soccer ball, basket ball or 5 the like.

An object of this invention is to provide a bladder with a valve construction wherein the valve is positioned inwardly of the bladder.

10 Another object of this invention is to provide a valve structure which is so constructed that it lies beneath the outer surface of the bladder and will therefore lie beneath the outer surface of the bladder casing so as not 15 to injure the players.

A further object of this invention is to provide in a valve construction of this character, means by which the bladder will not fall into the casing when it becomes deflated so that it will be an easy matter to reinflate 20 the bladder.

A still further object of this invention is to provide a bladder with a removable valve structure so that when the valve becomes 25 worn or unfit for use it may be readily replaced without the necessity of purchasing an entirely new bladder.

The above and various other objects and 30 advantages of this invention will in part be described in and in part be understood from the following detailed description of the present preferred embodiment, the same being illustrated in the accompanying drawing wherein:

35 Figure 1 is a fragmentary longitudinal section partly in detail of a device constructed according to the preferred embodiment of this invention;

40 Figure 2 is a side elevation of the inflated tube; and

Figure 3 is a sectional view taken on the line 3—3 of Figure 1.

Referring to the drawing wherein like numerals of reference designate corresponding 45 parts throughout the several views, the numeral 10 designates generally a bladder which is constructed of rubber or other resilient or flexible material which is adapted to be mounted in an outer casing of suitable 50 construction such as leather or the like and

which is commonly used in the playing of games of football, volley ball, soccer, or any game where an inflated ball is used. The bladder 10 is provided with an inwardly extending neck portion 11 which is vulcanized 55 or otherwise secured as at 12 to the bladder, and a valve member 13 of conventional construction is adapted to be mounted within the bladder 10.

The valve member 13 is provided with an 60 outer shell or casing 14 which is tubular in construction and is preferably formed of rubber or the like and is adapted to be interposed between the inwardly extending neck 11 and the outer surface of the valve 65 structure 13.

Preferably, the outer end of the valve 13 terminates at a point spaced inwardly from the outer surface of the bladder 10 so that when the bladder 10 is inflated (as with air 70 or the like) the tubular neck member 11 and the tubular shell 14 are subjected to pressure from within so as to firmly grip the valve 13 within the shell member 14, and the valve 13 is also positioned at a point spaced inwardly from the outer surface of the bladder 10 so as to prevent contact from the outside with the metallic valve structure 13. 75

The tubular shell 14 is preferably open at the opposite ends thereof so as to permit the 80 ingress and egress of air through the shell and likewise, the tubular shell 14 is provided with an outstanding annular rib 15 adjacent the inner end thereof which is adapted to seat in an annular recess 16 formed in the 85 inner periphery of the neck 11 so that when the tubular member 14 is inserted in the neck 11 it may be positioned thereinto for the desired distance and will not slip into the interior of the bladder. The valve covering 14 90 may also be secured to the valve 13 by other means, as by cementing, vulcanizing or the like, and the shell 14 may also be secured to the inwardly extending neck 11 by means of cementing, vulcanizing or the like. 95

The outer end of the tubular member 14 is preferably extended outwardly of the casing 10 for the desired distance and is likewise provided with an outstanding ring or flange 100 17 adjacent the outer end thereof. The ex-

tended or exposed portion of the shell 14 is adapted to be positioned in an annular recess 18 in a protecting flap 19, and the rib 17 is adapted to be positioned on the outer face of the flap 19 so as to retain the flap upon the tubular member 14.

The flap 19 may be secured in any desired manner to the outer shield or casing of the ball and when the ball becomes deflated, the 10 annular rib 17 will prevent the bladder from dropping into the casing so as to make it necessary to unlac the lacing in the outer casing.

In balls at present in use which are provided with an inwardly extending valve structure, the valve is sewed or otherwise secured to the outer casing by stitching and when the stitching becomes worn, the bladder will drop into the casing and it is necessary to 20 unlac the outer casing so as to properly position the valve which in most cases must again be sewed or otherwise secured to the outer casing whereas in the structure herein disclosed the annular rib 17 will prevent the 25 bladder from dropping into the casing when the bladder is deflated so that when it is desired to reinflate the bladder it will not be necessary to relace the outer casing and repair the same where it has been torn or broken.

30 In the use of this device, the tubular member 14 is adapted to extend or project outwardly of the bladder 10 and also extends outwardly of the flap 19 to a slight degree so that it will be substantially flush with the outer casing or covering so that when it is desired to reinflate the bladder it is only necessary to place a tubular member connected to a source of air pressure to the outer end 35 of the tube 14 and the air will pass into the bladder 10 through the valve 13.

It will be obvious from the foregoing that a valve structure has been provided wherein the valve is positioned inwardly of the bladder and the outer end of the valve casing 45 is positioned at a point inwardly from the outer surface of the bladder or the outer surface of the ball structure so that when the bladder is inflated, the pressure within the bladder will tend to constrict the neck 11 50 and the tubular shell 14 although it is of course to be understood that this pressure will not be sufficient to seal the tube 14 inasmuch as the valve structure 13 will effectively hold the air under pressure within the bladder 55 10, but the pressure within the bladder on the tubular shells 11 and 14 or that portion of these members positioned outwardly of the outer end of the valve structure 13 will have a tendency to cushion the valve structure 60 within the bladder and at the same time prevent any contact from the exterior with the metallic valve structure 13 so that with a ball having a bladder constructed according to my invention mounted therein, the ball 65 will not have what is commonly termed a

"dead spot" or a spot where no resiliency is present as in the structures where the metal valve is substantially flush with the outer ball casing.

It will, of course, be understood that various changes and modifications may be made in the details of construction and design of the above specifically described embodiment of this invention without departing from the spirit thereof, such changes and modifications being restricted only by the scope of the following claims.

What is claimed is:—

1. In combination with a bladder, an inwardly extending tubular neck secured to said bladder, a metallic valve, and an elongated open ended ribbed tubular member of flexible construction removably interposed between said neck and said valve, said valve being disposed in said member inwardly of the outer 80 surface of said bladder.

2. In combination with a resilient bladder, a resilient tubular neck secured to said bladder and extending inwardly from the outer surface thereof, a valve positioned in said neck, an elongated flexible tubular shell removably interposed between said neck and said valve, said valve being disposed in said shell inwardly of the outer surface of the bladder, said tubular shell having ribs adjacent each end and extending outwardly of said bladder, and means for removably securing said tubular shell to the outer covering for said bladder.

3. In combination with a resilient bladder, a resilient neck secured to said bladder and extending inwardly thereof, said neck having a grooved portion adjacent the inner end, a valve, an elongated flexible tube removably positioned about said valve, said tube having an annular rib adjacent the inner end portion thereof, said annular rib being adapted to seat in said grooved portion of said neck, means for securing said tube to said neck, means for securing said tube to said valve, said tube having an elongated extension positioned outwardly of the bladder, said outer extension having an annular rib, and an apertured flap positioned about said extension of said tube and adapted to engage against the inner edge of said rib.

In testimony whereof I hereunto affix my signature.

WILLIAM A. KNAUER.
